TREE FOR SHOES AND OTHER FOOTWEAR

James Franklin Clark and Edward Bowman
Clark, Toronto, Ontario, CanadaApplication June 9, 1934, Serial No. 729,791
In Canada May 12, 1934

7 Claims. (Cl. 12—128.2)

Our invention relates to improvements in trees for shoes and other footwear, and the object of the invention is to devise a tree particularly adaptable for holding an article of footwear in imperfect shape for window display by holding the sole firmly in position in relation to the upper and the flexible upper evenly distended at all points so that it will present a smooth exterior rounded surface and, therefore, an appearance most pleasing to the eye, and in which the tree body will fit any make of shoe without any adjustment, and it consists essentially of the arrangement and construction of parts as herein-after more particularly explained.

Fig. 1 is a sectional view of our tree applied to a shoe.

Fig. 2 is a perspective view of the body of the tree looking at the rear end.

Fig. 3 is a perspective view of the body of the tree looking at the front end with a portion of the cushion layer broken away to exhibit the shell forming the base support thereof.

Fig. 4 is a transverse section through Fig. 1.

Fig. 5 is a perspective view of a modified form.

Fig. 6 is a transverse sectional view through Fig. 5.

Fig. 7 is a sectional view through another modification applied to a shoe.

Fig. 8 is a transverse sectional view through another modification.

Fig. 9 illustrates a further modification.

Like characters of reference indicate corresponding parts in each figure.

Referring to Figs. 1, 2 and 3: 1 indicates the sole of a shoe and 2 the upper which is of comparatively flexible material, 3 the heel and 4 the heel counter stiffened in any suitable way and 5 the inner sole. 6 is a shell formed of aluminum, fibre or any other light sheet material and 25 forming generally to the shape of the interior of the shoe forepart, the bottom wall 6^a resting upon the inner sole and the upper wall 6^b forming the top and sides of the shell opposing and spaced from the upper. In the interspace 40 between the shell wall 6^b and upper is a layer 7 of resilient material such as sponge rubber which is cemented or otherwise suitably secured to the exterior surface of the wall 6^b. When the tree body is forced into the toe of the shoe, the layer 50 7 is compressed more or less at various points according to the shape of the shoe so as to evenly fill out the upper and give the exterior thereof a smooth rounder contour to enhance its appearance for window display.

Although we have described the above con-

struction as related to the toe portion of the shoe, it might be applied to any desired portion of the shoe or, in certain cases, to the whole shoe.

In order to hold the tree body in place, we provide a heel engaging portion 8 preferably formed of wire bent back upon itself in loop form, one end 8^a being secured to the shell 6 and the other end 8^b engaging in the teeth of an inclined rack 9 secured to the bottom wall 6^a of the shell 6 so as to increase or decrease the forward pressure of the tree body according to the style or shape of the shoe. The base 8^a of the loop is corrugated at 10 to more securely engage the counter of the shoe.

In order to increase the longitudinal stretch 15 of the shoe we may employ a tongue or strip 11 (see Fig. 7) extending rearwardly from the tree body and bent upward to fit the heel as indicated at 11^a, such upturned portion being tempered so as to tend to spring outward towards 20 the dotted position illustrated in this figure and thus exert a stretch between the toe and heel.

In Figs. 5 and 6 we show a modified form in which the bottom wall of the shell is dispensed with and the shell 12 made of resilient material 25 so that the sides will have outward pressure to hold the tree body in place. 13 and 14 are thumb grips by which the shell may be compressed inward so as to permit the withdrawal or insertion of the tree.

In Fig. 8 we show a further modification in which a body of cork 15 takes the place of the shell as a carrier for the resilient rubber pad 16.

Although we have described our construction as related to the ordinary shoe tree, it might be 35 used in a manikin where the foot forms a tree and to which, therefore, our construction would be applicable so that after the stocking is drawn onto the manikin any style or shape of shoe may be fitted on the manikin's foot and be firmly held 40 and maintain its perfect shape.

In the form shown in Fig. 9, the tree is provided with a flexible covering 17 formed of knitted or woven material so that it will stretch in all directions to snugly fit any shape of tree and 45 adapt itself to the shape of the shoe when the tree is inserted in the shoe and which is gathered together at the broad end of the tree to form a pull tab 18. When withdrawing the tree from a shoe pulling upon the tab causes the sides of 50 the tree to contract so as to allow of the tree slipping easily outward from the shoe without binding.

From this description it will be seen that we have devised a very simple, cheap, light and dura-

ble form of tree particularly adaptable for holding the flexible walls of a shoe or other footwear in place to fill out the shoe and impart to the exterior thereof a smooth, rounded surface so that the shoe, when in a store window, will be viewed to the best advantage and, at the same time, provide a tree which will fit various sizes and shapes of shoes.

What we claim as our invention is:

- 10 1. A shoe tree, for use with a shoe or other footwear, having a flexible upper and a comparatively rigid sole, comprising a body formed of sheet material, a layer of resilient material extending over the body and secured thereto to be compressed between the body and upper when inserted in the shoe, resilient means bearing against the heel end of the shoe for holding the tree body in place, such means comprising a rack member formed in the tree body, a wire secured at one end to the tree body and bent back upon itself to form a loop bearing at its closed end against the heel and at its free end engaging the rack.
- 15 2. A shoe tree, for use with a shoe or other footwear, having a flexible upper and a comparatively rigid sole, comprising a body formed of sheet material, a layer of resilient material extending over the body and secured thereto to be compressed between the body and upper when inserted in the shoe, resilient means bearing against the heel end of the shoe for holding the tree body in place, such means comprising a rack member formed in the tree body, a wire secured at one end to the tree body and bent back upon itself to form a loop bearing at its closed end against the heel and at its free end engaging the rack, and corrugations formed in the closed end of the loop to frictionally engage the shoe at the heel end.
- 20 3. A shoe tree comprising a hollow core formed of resilient material with sides exerting an outward pressure tending to hold the tree in place, said core having an open bottom and having an upper surface contour of the general shape of the fore part of a shoe upper and having on such surface a pad of cellular rubber extending forwardly from a position approximately corresponding to a shoe vamp-line toward the toe, said pad having an upper surface contour conforming generally to the contour of the flexible fore part of a shoe upper and being compressible over local areas by portions of a shoe upper which do not conform with the pad surface without extruding the surface of other portions of the pad said pad cooperating with the resilient material of said core to effect a uniform distension of the flexible portion of a shoe upper from its vamp line toward its toe.
- 25 4. A shoe tree comprising a core member having an upper surface conforming generally with the contour of the flexible fore-part of a shoe upper and having on such surface a pad member of cellular rubber extending forwardly from a position approximately corresponding to a shoe-vamp line toward the toe, said pad member having an upper surface contour conforming generally to the contour of the flexible fore-part of a

shoe upper and being compressible over local areas by portions of a shoe upper which do not conform with the pad surface without extruding the surface of other portions of the pad, and thereby effecting a uniform distension of the flexible portion of a shoe from its vamp line toward its toe, and means for compressing one of said members to facilitate the withdrawal of the tree from a shoe.

5 5. A shoe tree comprising a core member adapted to project into the fore-part of a shoe upper and having thereon a cellular rubber pad extending forwardly from a position approximately corresponding to a shoe-vamp line toward the toe, said pad having a surface contour conforming generally to the contour of the flexible fore-part of a shoe upper and being compressible over local areas by portions of a shoe upper fore-part which do not conform with the pad surface and without extruding the surface of other portions of the pad, and a flexible sheathing for said pad, said sheathing being provided with a pull member for drawing said sheathing tightly against and compressing said pad to facilitate the withdrawal of the tree from a shoe without binding.

6. A shoe tree comprising a core consisting of a lower wall of sheet material conforming generally with the contour of the sole of the fore-part of a shoe and an upper wall of sheet material connected at the toe with said lower wall and having an upper surface conforming generally with the contour of the flexible fore-part of the shoe upper, said upper wall diverging from the lower wall and forming therewith a mouth accessible through the throat of a shoe, and a sponge rubber pad on said upper surface, said pad having an upper surface contour conforming generally to the contour of the flexible fore-part of a shoe upper and being compressible over local areas by portions of a shoe upper fore-part which do not conform with the pad surface without extruding the surface of other portions of the pad.

7. A shoe tree comprising a core having a substantially unyielding lower member for directly engaging the inner sole of a shoe, said core having an upper surface contour of the general shape of the fore part of a shoe upper and having on such surface a pad of cellular rubber extending forwardly from a position approximately corresponding to a shoe vamp line of the shoe with which it is to be used toward the toe, said pad having an upper surface contour conforming generally to the contour of the flexible fore part of a shoe upper and being compressible over local areas by portions of a shoe upper which do not conform with the pad surface without extruding the surface of other portions of the pad, any thrust resulting from such compression being transmitted to the sole through said substantially unyielding lower member of the core, and a uniform distension of the flexible portion of a shoe upper from its vamp line toward its toe being thereby effected.
